UNITED STATES PATENT OFFICE.

GEORGE M. WILLIS, OF CHICAGO, ILLINOIS.

CHECKWRITER.

1,321,348.

Specification of Letters Patent. Patented Nov. 11, 1919.

Application filed April 11, 1918. Serial No. 227,871.

To all whom it may concern:

Be it known that I, GEORGE M. WILLIS, a citizen of the United States, residing at Chicago, in the county of Cook and State 5 of Illinois, have invented certain new and useful Improvements in Checkwriters, of which the following is a full, clear, concise, and exact description, reference being had to the accompanying drawings, forming a part 10 of this specification.

My invention relates to printing machines and particularly to that class of hand presses which are used for marking or impressing upon the face of a check, draft or other 15 negotiable instrument, the amount for which the instrument is payable.

Heretofore in the art it has been customary to provide the printing characters with serrated printing faces, which serrated printing 20 faces are adapted to coöperate with a platen having a correspondingly serrated impression face. This form of check-writer has been found to be unsatisfactory, due to the difficulty in properly registering the 25 coöperating serrated faces of the printing characters and the platen, and also to the comparatively short time in which these serrated faces become worn out.

My invention consists of a novel construction 30 of check writer, wherein the impression face of the platen and the coöoperating faces of the printing characters are relatively smooth, thereby providing a device of great efficiency and durability.

Due to the great complexity of most of 35 the devices now in use and to the necessity for placing such devices in the hands of persons usually not skilled in the use thereof, I contemplate an improved check writer of 40 extremely simple and inexpensive construction which may be operated by any person, whether skilled in the use thereof or not.

According to my invention, the check or other negotiable instrument upon which the 45 amount payable is to be marked or impressed is perforated within the area within which the amount is to be printed, a series of smooth faced printing characters having been previously inked and adapted to ink 50 the upstanding edges of the openings formed upon perforating the paper, then coöperating with a smooth faced platen to crush or flatten these upstanding edges, thereby forcing the ink into the fiber of the paper and

making it impossible to remove the ink or 55 otherwise alter the amount payable without mutilating the face of the paper.

As the check blanks, drafts and the like now in general use are provided with a blank space with the word dollars printed at the 60 end thereof, I mark or impress the amount upon the check in dollars and hundredth parts of a dollar instead of using a decimal point which might be easily removed or of printing the amount in dollars and cents 65 with the word cents following the amount, as is the present practice. The check writer of my invention is provided with a sight indicator which discloses to the operator the particular printing characters that are in 70 position to be impressed upon the check, thereby minimizing the possibility of impressing the amount incorrectly upon the check.

I find this construction to be highly advan- 75 tageous, as it is simple, reliable and durable. I do not intend to be limited to the precise construction which I disclose herein, as I consider the various means which may be devised for perforating the check and then 80 marking or impressing the amount payable upon the perforated area thereof, to be but different ways or routes for arriving at the same desirable result, and hence I consider them to be within the scope of my invention. 85 In the accompanying drawings forming a part of this specification,

Figure 1 is a plan view of the check writer of my invention;

Fig. 2 is a longitudinal sectional view 90 taken substantially on the line 2—2 of Fig. 1;

Fig. 3 is a transverse sectional view taken on the line 3—3 of Fig. 2;

Fig. 4 is a diagrammatic illustration of 95 the fool proof mechanism employed in connection with the check writer of my invention;

Fig. 5 is a fragmentary view of a check having been embossed with my improved 100 check writer;

Fig. 6 is a fragmentary view on an enlarged scale, showing the coöperative action of the printing characters with the perforated area of the check; and

Fig. 7 is a perspective view of a stripper 105 for removing the check from the perforating pins upon the perforation of the check.

The check writer of my invention comprises a substantially rectangular casing 1, preferably fashioned from some suitable sheet metal or the like the side walls 2 and 3 of which are suitably slotted to receive a check, draft or other negotiable instrument, as will be hereinafter described. The casing 1 is provided with a guiding member 4 extending transversely thereof and into which the check is adapted to be inserted when it is desired to mark or emboss the same. The guiding member 4 comprises two pairs of suitably spaced plates of sheet metal extending transversely of the casing 1, and spaced longitudinally at the center so that the platen may be lifted therethrough, as will be hereinafter described, these plates being spaced slightly in a vertical plane for the reception of a check or the like therebetween. The outer edges of the upper plates of the guiding member 4 are bent at substantially right angles thereto to facilitate soldering, riveting or otherwise, suitably securing these plates to the opposite side walls 2 and 3 respectively of the casing 1. The lower plates of the guiding member 4 project from the opposite sides of the casing 1, as shown in Figs. 1 and 3, thereby forming a ledge on either side of the casing 1, to facilitate the ready introduction of a check, draft or the like into the guiding member 4.

Above the transverse guiding member 4 are mounted the type bearing bars 5 which carry upon their under surfaces suitable printing or embossing characters 6. The type bearing bars 5, which are substantially I shaped in cross-section, are mounted for longitudinal movement between a plurality of horizontally disposed supporting bars 7, the upper enlarged portions of the I shaped type-bearing bars 5 bearing upon the upper surfaces of these supporting bars. A pair of intermediate side walls 8 and 9 are disposed between and substantially parallel to the side walls 2 and 3 of the casing 1 as shown in Fig. 3. The intermediate side walls 8 and 9 are adapted to carry or have secured thereto such parts of the device as will be herein-after described, thereby obviating the necessity of riveting to or otherwise marring the outside appearance of the side walls 2 and 3.

The horizontally disposed supporting bars 7 are supported at their opposite ends by transversely extending supporting brackets 10 and 11. The outer ends of the transverse supporting brackets 10 and 11 are bent back at substantially right angles to the transverse portion thereof to facilitate connection, as by rivets or otherwise, to the intermediate side walls 8 and 9. The transversely extending portions of the supporting brackets 10 and 11 are provided with a plurality of apertures for receiving the opposite ends of the supporting bars 7, which extend there-

through as shown in Fig. 2, longitudinal displacement of these supporting bars being prevented by engagement of their opposite ends with the front and rear walls respectively of the casing 1.

The type bearing bars 5 are provided with suitable tongues 12, as shown in Fig. 2, preferably formed integral therewith and projecting horizontally from the inner end thereof, these horizontally projecting tongues 12 being provided with vertical apertures therethrough. Each of the type-bearing bars 5 is provided with an indicating strip 13, preferably formed of sheet metal and faced with celluloid or the like, these indicating strips 13 being disposed adjacent the under surface of the top of the casing 1 and adapted to move in unison with the type bearing bars 5 to disclose to the operator through an appropriate transverse aperture 14 provided in the top of the casing 1, the particular printing characters that are in position to be marked or impressed upon the check. The inner end of the indicating strips 13 are provided with downwardly projecting fingers 15, either formed integral therewith or suitably secured thereto. The lower free ends of the downwardly projecting fingers 15 are adapted to be received in the vertical apertures provided in the horizontally projecting tongues 12 of the type bearing bars 5, so that upon movement of the indicating strip 13 the type bearing bar 5 will move in unison therewith. The indicating strip 13 has a series of digits on the upper surface thereof, corresponding to and coinciding vertically with the printing characters provided on the under surface of the type bearing bars 5. As the check blanks, drafts and the like, now in general use, are provided with a blank space with the word dollars printed at the end thereof, I employ type bearing bars that are adapted to mark or impress the amount upon the checking dollars and hundredth parts of a dollar, as shown in Figs. 1 and 5. The type bearing bar adjacent the right hand side of the device is provided with the digits 0 over 100 to 9 over 100, thereby indicating the hundredth parts of a dollar, the type bearing bar adjacent thereto being provided with the digits 0 to 9 positioned to align with the digits 1 to 9 of the hundredth indicating bar, each of the digits of this bar which indicates the tenth parts of a dollar being preceded by the word "and". It is now apparent that these two type bearing bars can be quickly positioned to produce any hundredth part of a dollar. Each of the type bearing bars to the left of the tenth and hundredth bars is provided with the digits 0 to 9, the 1 being preceded by some suitable spacing character so that when an amount such as 1000 dollars is required upon the check the space to the left of the amount will be suitably marked

or embossed by the spacing character provided on the ten thousand bar thereby preventing alteration of the check by placing an additional digit to the left of the amount, 5 the "Pay" bar 61 being mounted rigidly in the casing.

Upwardly projecting fingers 16 are provided on the inner ends of the indicating strips 13, these upwardly projecting fingers 10 16 projecting through appropriate longitudinal slots 17, provided in the top of the casing 1. The indicating strips 13 and consequently the type bearing bars 5 are adapted 15 for longitudinal movement in the casing 1 by means of the buttons or finger pieces 18 provided on the upper end of the upwardly projecting fingers 16.

The opposite ends of the indicating strips 13 are adapted to be guided by means of 20 suitable fingers 19 which project upwardly through appropriate longitudinal slots provided in the top of the casing 1, the upper ends of these fingers 19 being headed or flattened over to prevent displacement there- 25 of. It will now be apparent that to set the printing characters to any amount that is desired to be marked or impressed upon the check, all that is necessary is to shift the type bearing bars 5 by means of the finger 30 pieces 18, the indicating strips 13 disclosing to the operator through the transverse slot 14 the exact setting of the device, as shown in Fig. 1.

An inking pad 20, having a rubber or felt 35 pad or cushion 21 mounted upon the under face thereof is arranged for longitudinal movement just above the guiding member 4, the guiding member 4 being inclined toward the inner end of the casing 1, so that 40 the inking pad 20 will clear the type bearing bars 5 when in the inoperative position, as shown in Fig. 2. The ends of the inking pad 20 are carried by suitable arms 22, the opposite ends of which are mounted upon a 45 cross shaft 23. The cross shaft 23 extends transversely across the casing 1, its opposite ends being guided in appropriate slots provided in the intermediate side walls 8 and 9.

50 The perforating and impressing mechanism comprises a transversely extending plate 24, the opposite ends 25 and 26 of which are bent downwardly adjacent the intermediate side walls 8 and 9 at substantially right angles to the transversely extending portion of the plate. The upper face of the transverse plate 24 is provided with a plurality of upwardly projecting pins 27, as shown in Fig. 2, these pins being 55 adapted to coöperate with the pad or cushion 21 provided upon the under face of the inking pad 20 to perforate the check when the transverse plate 24 is lifted, as will be hereinafter described. The downwardly ex- 60 tending portions 25 and 26 of the transverse

plate 24 are guided in a pair of U-shaped guiding members 28. The U-shaped guiding members 28 are secured to, as by suitable rivets or otherwise, the inner faces of the intermediate side walls 8 and 9 respectively. The lower free ends of the downwardly extending portions 25 and 26 of the transverse plate 24 are mounted upon a cross shaft 29. The opposite ends of the cross shaft 29 extend through and are guided 70 for vertical movement in suitable slots provided in the intermediate side walls 8 and 9 respectively. The ends of the cross shaft 29 are provided with suitable rollers 30 mounted thereupon adjacent the outer faces 80 of the intermediate walls 8 and 9. The rollers 30 are adapted to be engaged by suitable lifting cams arranged thereunder, thereby lifting the transverse plate 24 to perforate the paper and to impress the amount 85 payable in this perforated area as will be hereinafter described.

A cross shaft 31, adapted to be operated by a crank 32 and a handle 33 extends horizontally through the side wall 3 and the 90 intermediate side walls 8 and 9 respectively of the casing 1, its opposite free end terminating between the intermediate wall 8 and the side wall 2. The cross shaft 31 is provided with a pair of lifting cams mounted 95 thereupon, just beneath the rollers 30 and adjacent the outer faces of the intermediate walls 8 and 9 respectively. These lifting cams, as shown in Fig. 2 are provided with a pair of lifting fingers 34 and 35 with a 100 depressed portion 36 therebetween.

Due to the necessity of placing devices of this class in the hands of persons usually not skilled in the use thereof, and the consequent need of a device requiring few 105 manual operations, and little prethought, I have provided for automatically alining the printing characters before marking or impressing them upon the face of the check. To this end the upper surfaces of the type 110 bearing bars 5 are provided with a series of transverse channels 37 formed therein, these transverse channels 37 coinciding vertically with the printing characters 6 on the under surface of the type bearing bars. A spring 115 pressed alining bar 38 extending transversely across the upper surfaces of the type bearing bars 5 is adapted to coöperate with the transverse channels 37 provided therein, to properly aline the type bearing bars 5 upon 120 operation of the crank 32, as will be hereinafter described. Spring strips 39 are mounted as at 40 upon each of the outer faces of the intermediate walls 8 and 9 of the casing 1. The downwardly extending arms of these 125 spring strips are provided with horizontally extending portions 57, bent at substantially right angles thereto, the free ends of these horizontal portions bearing upon the upper peripheries of the rollers 30, provided on the 130

cross shaft 29. The free ends of the arms of these spring strips which extend substantially horizontally from the pivotal mounting 40 engage the under surface of the inner 5 end of a rocker arm 41. The opposite ends of the rocker arms 41, which are pivoted at their central position to the intermediate walls 8 and 9 respectively, engage the opposite ends of the alining bar 38 so that the 10 alining bar will be pressed downwardly into the transverse channels 37 provided in the type bearing bars 5 to aline the printing character 6 upon rotation of the shaft 31 by means of the crank 32 and handle 33.

15 A relatively smooth faced platen 42 pivotally mounted at its opposite ends to the downwardly extending portions 25 and 26 of the transverse perforating plate 24 by means of the arms 43 is normally retained in 20 the position shown in Fig. 2 by means of suitable coiled springs 44.

A pair of leaf springs 45, shown in Figs. 2 and 3 are mounted upon the transverse shaft 31 adjacent the intermediate walls 8 25 and 9 respectively of the casing 1.

Referring to Fig. 2 it will be seen that the leaf springs 45 normally project downwardly from the cross shaft 31, the downwardly projecting portion being just below 30 the depressed portion 36 of the lifting cam. This arrangement is so that upon rotation 35 of the cross shaft 31, by means of the handle 33 and the crank 32 in a counterclockwise direction, the leaf springs 45 will not engage the downwardly extending arms 43 of the platen 42 until the lifting cams 34 have engaged the rollers 30, thereby lifting the transverse perforating plate 24 to perforate the check. Further rotation of the cross 40 shaft 31 will cause the rollers 30 to drop from the lifting cams 34 into the depressed portion 36. The leaf springs 45 are then adapted to engage the downwardly projecting arms 43 of the platen 42 and thereby 45 swing the platen about the pivot 46 against the tension of the spring 44 into a position covering the upwardly projecting perforating pins 27, provided on the upper surface of the transverse plate 24. Still further rotation 50 of the cross shaft 31, the leaf springs 45 giving sufficiently to allow of such rotation, brings the lifting cams 35 into engagement with the rollers 30, thereby lifting the transverse plate 24 with the platen 42, covering 55 the perforating pins 27 provided on the upper surface thereof, the platen 42 being suitably spaced from the perforating pins 27 by means of suitable spacing blocks provided upon either end of the platen. The 60 platen 42 will be thereby lifted against the under surface of the check up through the guiding member 4, which is suitably apertured therefor as shown in Fig. 2, into coöperation with the printing characters 6 65 provided on the under surface of the type

bearing bars 5, thereby impressing upon the perforated area of the check, the amount as indicated through the slight aperture 17 by means of the indicating strips 13.

The cross shaft 23 upon which the inking 70 pad supporting arms 22 are mounted, is normally held in the position shown in Fig. 2 by means of a pair of substantially vertical leaf springs 47. The leaf springs 47, one of which is provided adjacent each of the 75 intermediate walls 8 and 9 respectively, are securely mounted upon suitable brackets 48, these brackets being suitably secured to the intermediate side walls 8 and 9 of the casing 1.

80 Motion is imparted from the transverse shaft 31 to the inking pad 20 by means of a substantially horizontal lever arm 49, shown in Fig. 2. The lever arm 49 is pivoted eccentrically upon the outer end of the 85 shaft 31, the opposite end of this lever arm being suitably notched to engage a pin 50, projecting from a lever 51. The lever 51, the lower end of which is pivotally mounted at 52 to the intermediate side wall 8, has 90 a spring arm 53 suitably secured to the upper free end thereof. The lever arm 51 is preferably bent inwardly intermediate its length so that the spring arm 53 will engage the cross shaft 23, substantially in the center 95 thereof.

It will now be apparent that upon rotating the transverse shaft 31 by means of the crank 32, the lever arm 49 will move eccentrically about the end of the shaft 31, thereby swinging the lever 51 about its pivot 52 and consequently causing engagement of the spring arm 53, which is less resilient than the leaf springs 47, with the cross shaft 23, to move the cross shaft 23 and inking pad 100 105 20 supported thereby, inwardly across the face of the printing characters that are in position to be impressed upon the check, into the position shown in dotted lines in Fig. 2.

110 It is, of course, understood that the printing characters 6 were previously alined by engagement of the rollers 30 in their upward movement with the horizontally extending portions 57 of the spring strips 39. Further rotation of the shaft 31, the spring 115 arm 53 being relatively stronger than the leaf spring 47, but being sufficiently flexible to allow of such rotation, causes engagement of the lifting cams 34 with the rollers 30 to lift the transverse plate 24, thereby forcing 120 125 the perforating pins 27 through the check and into the pad or cushion 21 provided on the under surface of the inking pad 20.

Still further rotation of the shaft 31 in a counterclockwise direction causes the rollers 125 30 to drop from the cams 34 into the depressed portions 36, although not shown, it is understood that spring means may be employed in connection herewith, thus withdrawing the perforating pins 27 from the 130

check. The lever arm 49 is provided with a notch 54 so positioned that the inclined shoulder thereof will engage a suitable knockout pin 55 just after withdrawal of 5 the perforating pins from the check. This engagement of the inclined shoulder of the notch 54 with the knockout pin 55 moves the lever arm 49 upwardly about the shaft 31 against the tension of a suitable spring 10 56, thereby causing the notched free end of the lever to disengage the pin 50 projecting from the lever arm 51, thereby allowing the leaf springs 47, by reason of their engagement with the transverse shaft 23, to move 15 the inking pad 20 into the position shown in Fig. 2.

Further rotation of the shaft 31 causes the platen 42 to be interposed between the perforating pins 27 and the check, as has 20 been heretofore explained, the platen 42 then being lifted and coöperating with the printing characters 6 impresses the amount payable upon the perforated area of the check. After setting the printing characters 25 at the required amount, placing the check in the transverse guiding member 4 and properly marking or embossing the check by a single movement of the crank 33 through substantially less than 180°, the 30 crank is then moved back into its normal position shown in Fig. 1, preferably by means of a suitable spring which may be coiled about the shaft 31 as is well understood in the art, thereby allowing the 35 notched free end of the lever 49 to again engage the pin 50 of the lever 51. Suitable pins 61 and 62 project outwardly horizontally from the side wall 3 of the casing 1 these pins serving as stops to limit the movement 40 of the crank 32.

As shown in Fig. 2, I have provided a door 58 in the outer end of the casing 1, thereby allowing access to the interior of the casing when it is desired to replenish the 45 supply of ink in the inking pad 20, this pad functioning most advantageously when the ink therein is kept in a more or less hygroscopic state.

In Fig. 4 I have shown diagrammatically 50 fool proof mechanism, which I contemplate employing to prevent the insertion of a check or the like into the guiding member 4 when the crank 32 is out of its normal position. It is apparent that if a check were 55 inserted when the rollers 30 are in engagement with the depressed portion 36 of the lifting cans, operation of the crank 32 would print the amount upon the check without perforating the same. To guard against 60 this I have provided the interconnected pins 65, one of which projects upwardly adjacent each side of the casing 1. The pins 65 are normally projected upwardly through suitable apertures provided in the lower plate 65 of the guiding member 4 and into engage-

ment with the upper plate of the guiding member by means of the leaf spring 66. A lever arm, 67, pivotally mounted at 68 is provided with an upwardly extending portion 69, this upwardly extending portion 70 having a pin projecting horizontally therefrom, out through a suitable slot in the casting 1, or being otherwise adapted to be engaged by the crank 32, just before it engages the stop 61. Engagement of the crank 32 75 with the lever 67 moves the same downwardly about the pivot 68 and into engagement with the leaf spring 66, thereby withdrawing the pins 65 from the guiding member 4. Movement of the crank 32 away 80 from the stop 61 releases the pins 65 allowing them to be projected upwardly through the apertures provided in the lower plate of the guiding member 4, thereby preventing the insertion of a check or the like in the 85 guiding member until the crank is returned to its normal position. Upon placing a check or the like in the guiding member 4 and moving the crank 32 away from the stop 61, the pins 65 will be projected up 90 through the lower plate of the guiding member, thereby holding the check securely therein, until the same has been properly embossed and the crank has been returned to its normal position. 95

In Fig. 6 I have shown on an enlarged scale, the coöperative action of the printing characters with the perforated area of the check. It is apparent that the upstanding ragged edges 59, formed upon perforating the paper 60, will be the first to engage the inked faces of the printing characters 6 upon the upward movement of the platen 42. As the platen 42 is moved farther upwardly, the upstanding thoroughly inked edges 95 of 100 the paper 60 will be crushed or flattened, by the coöperation of the platen 42 with the printing characters 6 thereby forcing the ink into the fiber of the paper and making it impossible to remove the ink or otherwise 105 alter the amount payable without mutilating the face of the paper 60. 110

In Fig. 7 I have shown in perspective a stripper for removing the check from the perforating pins upon the perforation of the 115 check. The stripper 70 comprises a rectangular open plate 71, the longest edges thereof being bent downwardly at substantially right angles thereto, as shown at 72 and 73. The downwardly extending portions 72 and 120 73 of the open plate 71 are slotted as shown at 74 for the reception of suitable pins 75 therethrough, the pins 75 projecting substantially horizontally from the transverse plate 24. The open plate 71, which is 125 guided by the pins 75 is normally held in the raised position by the leaf springs 76, one end of each of these springs 76 being securely mounted in the transverse plate 24. 130

It will now be apparent that upon lifting

the transverse perforating plate 24 to perforate the check, the open plate 71 will engage the bottom surface of the check before the perforating pins 27, thereby holding the 5 check securely against the pad 21 during the perforation of the check, the open area of the plate 71 being sufficiently large to allow the perforating pins to pass there-through against the tension of the leaf 10 springs 76.

Upon withdrawing the perforating pins from the check the plate 71 will remain in engagement therewith until the pins have been withdrawn, thereby insuring proper 15 removal of the check from the pins. Further operation of the device removes the open plate 71 from its engagement with the under surface of the check, just before the inking pad 20 is moved to the right, as has 20 been explained.

I do not intend to be limited to the precise details of construction shown and described.

I claim:

1. In a device of the class described, a 25 casing having a predetermined printing space therein, a plurality of type bearing members, each of said type bearing members having a series of substantially smooth-faced printing characters thereon, said 30 printing characters adapted to be brought into selective registration with said printing space, perforating means operating in said printing space for simultaneously perforating the entire printing area of the 35 check in said printing space, and impression means coöperating with said printing characters for simultaneously impressing all of the selected printing characters in the perforated area of the check.

2. In a check protecting device, a plurality of type bearing members, each of said type bearing members having a series of substantially smooth faced printing characters thereon, said check protecting device 45 having a predetermined printing space thereon, said printing characters adapted to be brought into selective registration with said printing space, perforating means operating in said printing space for simultaneously 50 perforating the entire printing area of the check, and impression means for coöperating with said printing characters.

3. In a check protecting device, a plurality of type bearing members, each of said type bearing members having a series of substantially smooth faced printing characters thereon, said check protecting device having a definite printing space thereon, said printing characters adapted to be 60 brought into selective registration with said printing space, perforating means operating in said printing space for simultaneously perforating the entire printing area of the check, and impression means coöperating 65 with said printing characters for simul-

taneously impressing all of the selected printing characters in the perforated area of the check.

4. In a device of the class described, a plurality of substantially smooth-faced 70 printing characters adapted to be brought into printing position, perforating means facing in opposition to the selected printing character, the check being adapted for insertion between the selected printing 75 character and the perforating means, said perforating means being aligned directly opposite the selected printing character and operative to perforate the printing area of the check prior to the printing thereof. 80

5. The method of embossing a check or the like, which comprises perforating the check with a plurality of fine circular needle-like holes from only one side thereof by a plurality of perforating points moving substantially normal to the plane of the check, thereby raising substantially continuous edges and fibers around the circular perforations, and then impressing printing characters upon the opposite side of said 90 perforated area.

6. The method of embossing a thin sheet which comprises simultaneously perforating the entire area to be embossed by a plurality of fine needle-like points moving substantially normal to the plane of the sheet, forcing the broken edges to one side, applying ink to the broken edges and then pressing the broken edges into substantial alignment with the sheet, said sheet remaining in 100 a substantially stationary position during all of said operations.

7. In a device of the class described, printing mechanism comprising a plurality of printing characters adapted to be brought 105 into register with a printing line in said device, impression means coöperating with said printing characters, and perforating mechanism adapted to perforate the entire area of the check coincident with said printing line at one operation, said perforating mechanism operating independently of said printing mechanism and prior to the operation thereof. 110

8. In a device of the class described, a 115 plurality of printing characters adapted to be brought into register with a printing line, perforating means adapted to perforate the entire area of the check coincident with said printing line at one operation, and a 120 platen movable into alignment with said printing line and adapted to simultaneously impress the selected group of printing characters into the perforated area of the check. 125

9. In a device of the class described, a plurality of printing characters adapted to be brought into register with a printing line in said device, perforating means, a 130 platen member, and means for alternately

- moving said perforating means and said platen member into simultaneous contact with the entire area of the check coincident with said printing line.
- 5 10. In a device of the class described, a plurality of substantially smooth faced printing characters adapted to be brought into register with a printing line in said device, perforating means, a platen member, 10 and means for alternately moving first said perforating means and then said platen member into operative position in register with said printing line.
11. In a device of the class described, a plurality of printing characters adapted to be brought into register with a printing line, a perforating plate having a plurality of perforating projections thereon, said perforating plates being alined directly opposite the selected printing characters, and a platen member adapted to be moved between said perforating plate and the perforated area of the check into said printed line.
12. In a device of the class described, a plurality of printing characters adapted to be brought into register with a printing line, a perforating plate beneath said printing line, a movable platen member adjacent said printing line, means for raising said perforating plate for perforating the check, and means for moving said platen member over said perforating plate into said printing line in position for coöperation with said printing characters.
13. In a device of the class described, a plurality of printing characters adapted to be brought into register with a printing line, a perforating plate beneath said printing line, a movable platen member adjacent said printing line, an operating shaft, cam means on said shaft for raising said perforating plate into said printing line, and arms on said shaft for swinging said platen member over said perforating plate into said printing line in position for coöperation with said printing characters.
14. In combination, a plurality of printing characters adapted to be brought into register with a printing line, perforating means independent of said printing characters adapted to perforate the area of the check coincident with said printing line, a matrix adapted for movement into and out of said printing line for coöperation with said perforating means and means operating with said matrix for inking the printing characters in register with said printing line.
15. In combination, a plurality of printing characters adapted to be brought into register with a printing line, perforating means independent of said printing characters adapted to perforate the area of the check coincident with said printing line, a matrix adapted for movement into and out of said printing line for coöperation with
- said perforating means and an inking pad carried by said matrix and adapted to ink said printing characters.
16. In a check writer, a plurality of type bearing elements having printing characters adapted to be brought into register with a printing line, each of said type bearing elements having depressions formed therein in sequence with said printing characters, a common alining bar for all of said type bearing elements, spring means for normally retaining said alining bar in said depressions, a platen adapted for coöperation with said printing characters and means operating upon the coöperation of said platen with said printing characters for forcibly pressing said alining bar into said depressions.
17. In a check writer the combination of a casing, said casing having a slot therein for receiving a check, printing mechanism in said casing, perforating mechanism in said casing, an operating crank for operating both of said mechanisms by a complete stroke thereof, a detent pin operable to obstruct said slot to prevent insertion of a check in said casing, and yieldable means controlled by said operating crank for moving said detent to its obstructing position upon the initial movement of said operating crank.
18. The herein described method of impressing characters on a thin sheet which consists in perforating the sheet from one side thereof with closely related fine needle-like perforations of circular formation, thereby raising substantially continuous edges and fibers around said circular perforations upon the opposite surface of said sheet, then inking said raised edges and fibers on definite areas to indicate printing characters, then compressing the sheet over said printed areas to force said projecting edges and fibers back into the plane of the sheet.
19. The herein described method of impressing printing characters upon a thin sheet which consists in perforating the sheet over a selected area from one side of the sheet with closely related fine needle-like holes of circular formation, then impressing inking characters upon the reverse side of the sheet upon said perforated areas with sufficient pressure to force the projecting edges and fibers back into the plane of the sheet.
20. The herein described method of impressing printing characters upon a thin sheet which consists in forcing a plurality of closely related circular needle points through the sheet from one side thereof, thereby closely perforating the sheet with a plurality of minute circular perforations and raising substantially continuous edges and fibers around said circular perforations

- upon the opposite side of said sheet, and impressing printing characters upon the raised edges and fibers with sufficient pressure to force same back into the plane of the sheet.
21. The herein described method of impressing printing characters upon a check which consists in placing a check in a definite position, and while it is in such position and without movement of the check, subjecting the check to the perforating action of a plurality of closely related circular needle points to the extent of raising substantially continuous edges and fibers of substantially uniform height around the circular perforations upon the opposite side of the check, then while the check is still held in said position impressing inking characters upon said perforated area upon said raised edges and fibers with sufficient pressure to force said edges and fibers back into the plane of the check.
22. In a check writer the combination of a check guide a plurality of closely grouped perforating needles having parallel axes, a matrix for coöperation therewith, means for effecting an axial movement of said needles relative to said matrix to force said needles through a check in said guide, and printing mechanism operable after said perforating operation for printing upon the perforated area of the check, said perforating needles and said printing mechanism arranged to operate on opposite sides of said check.
23. In a check writer the combination of a plurality of closely grouped perforating needles having parallel axes, a matrix for coöperation therewith, means for effecting a straight line movement between said needles and matrix to force said needles through the check from the rear side thereof, and printing mechanism operable after said perforating operation for printing upon the perforated area of the check on the front side thereof.
24. In a check writer the combination of a perforating means including a plurality of parallel needles and mechanism for effecting axial movement of said needles relative to the check to perforate the check from one side thereof, and printing means for printing upon the perforated area of the check on the other side thereof after the perforating operation.
25. In a check writer the combination of a perforating means for perforating the check from one side thereof, said means including a plurality of parallel needles having a straight line movement relative to the check, oppositely disposed printing characters for operating upon the perforated area of the check on the other side thereof after the perforating operation, and means interposable between said perforating means and the check for coöperation with said printing characters to effect the printing impression.
26. In a check writer the combination of perforating points for perforating the check from one side thereof, oppositely disposed printing characters for operating upon the perforated area of the check upon the other side thereof after the perforating operation, a matrix interposable between said printing characters and the check for coöperation with said perforating points, and a platen interposable between said points and said check for coöperation with said printing characters.
27. In a check writer the combination of perforating points for perforating the check from one side thereof, oppositely disposed printing characters for operating upon the perforated area of the check on the other side thereof after the perforating operation, and means interposable between said perforating points and the check for coöperation with said printing characters to effect the printing impressions.

In witness whereof I hereunto subscribe my name this 28th day of March, A. D. 90 1918.

GEORGE M. WILLIS.
